UNITED STATES PATENT OFFICE.

SOL S. SONNEBORN, OF BROOKLYN, NEW YORK, ASSIGNOR TO HOPEWELL INSULATION & MFG. CO., A CORPORATION OF VIRGINIA.

STRESS-DISTRIBUTED INSULATOR.

Application filed April 24, 1918. Serial No. 230,432.

To all whom it may concern:

Be it known that I, SOL S. SONNEBORN, a citizen of the United States, and a resident of Brooklyn, county of Kings, and State of New York, have invented certain new and useful Improvements in Stress-Distributed Insulators, set forth in the following specification.

This invention relates to strain insulators, particularly of the high tension type and of the type subjected to considerable mechanical stress. The invention resides both in an individual strain insulator unit and in part in a connected string of such units.

15 The broad object of my invention is to provide a strain insulator which will withstand both electric and mechanical stress better than has heretofore been accomplished. A further object of my invention is to minimize the size of a high tension strain insulator and the cost of its construction.

To the above ends it is one of my objects to distribute the electro-static stress between the crossing contiguous parts of a strain insulator which are subjected to wide differences of potential. It is also one of my objects to provide insulating material of a shape and character, between the parts subjected to severe mechanical stresses, which 30 will best withstand such stresses and, in connection with this objective, I further propose to distribute the mechanical stresses to prevent a tendency for localized strain.

The above and further detail features of my invention will better be understood by reference to the illustrative embodiment described in the following specification in connection with the accompanying drawings, which form a part hereof, in which like characters designate corresponding parts in the several figures and in which—

Figure 1 is a vertical section through one of my insulator units, with parts shown in elevation and with its connection to a second unit of a string indicated;

Figure 2 is a vertical section at right angles to the showing of Figure 1, taken through line II—II of Fig. 1;

Figure 3 is a detail plan of a stress-distributing plate; and

Figure 4 is a plan view of the insulator cross bars and stress-distributing saddle before the same have been moulded into the imbedding insulating material.

55 In the drawings, A indicates an individual

insulator unit embodying my invention, being in this instance shown as the top unit of a string and connected with the second unit B of a string, which is identical with the unit A. At this stage of the description the peculiar symmetrical construction of my insulator may be appreciated by noting that the insulator unit proper as shown in Figs. 1 and 2 has the identical appearance, in these Figures 1 and 2, provided that one of the figures 60 is inverted and then compared with the other.

Each unit comprises a pair of yokes C and D, which in this embodiment have their cross bars 1 and 2 in interlinking relation. 70 Outwardly extending from the cross bar 1 in the yoke construction is a pair of tension legs 3 and 4 and from the cross bar 2 a similar pair of tension legs 5 and 6. Each cross bar preferably comprises a metal tube 75 7 threaded at the ends to have threaded engagement with the threaded eyes 8 of the tension legs and to receive a lock nut 9. It is also preferably reinforced by an internal bar or pin 10, driven through the tubular bar 80 7, by which laminated or built-up construction greatly increased mechanical strength is imparted. Each tension leg preferably comprises at its outer end an internally threaded nipple 11 having threaded engagement with the threaded outer end of each part 12 and providing a seat for the threaded end of an eye-bolt 13, the stem of which anchors one end of a stress-distributing plate 85 E, the central portion 14 of which is preferably flared into a disk-shaped formation from which the perforated lugs 15 extend.

Although the yokes C and D have been described as built up of a number of parts, which is the preferred construction, it is to 95 be understood that the expression "yoke" is used in its broadest sense and does not exclude a construction in which a single bar is bent into U-shape. Although for some purposes, for example the reduction of heating from hysteresis, it may be preferable to construct the yokes of non-magnetic metal such as brass, nevertheless, for purposes of great mechanical strength, it is considered 100 preferably to have the cross bars constructed, both the tubular part and the reinforcing pin, of a high grade of steel.

Surrounding each cross bar 1 and 2 is a tube of insulating material. That for the bar 1 is indicated by the numeral 16 and is 110

shown as a single tube preferably of compressed fiber of the type capable of withstanding great mechanical pressure and having no tendency to soften upon heating. 5 The insulating tube 17 for the cross bar 2 should be made of the same kind of insulating material. A preferable construction is shown built up of a plurality of tubular sections, which of course may be the construction for the tube 16, it being desired to convey the idea that either or both tubes may be of unitary or laminated construction.

15 Interposed between the insulating tubes 16 and 17 is a saddle F of conducting metal, preferably brass, which interposes a zone of metal 18 between the insulating tubes 16 and 17 and provides transversely arranged channels 20 and 21 through which the tubes 20 16 and 17 may pass to be embraced by the wings 22 for the tube 16 and 23 for the tube 17. The space 24 between each pair of wings 22 and 23 is preferably centrally enlarged to form the circular opening 25 directly 25 above the crossing point for the cross bars 1 and 2 so that the electro-static distributing effect of the enlargement 14 of each stress-distributor E may be greater.

At this point it should be noted that 30 electro-static stress between the bar 1 and the bar 2 would normally be localized in a small area representing the shortest distance between these two bars. As these two bars are circular and are arranged in planes 35 at right angles to each other, these localities of shortest distance apart would approximate points. However, such is not the case in my insulator. The saddle of conducting material F interposed between the cross bars 40 increases the electro-static area between the cross bars so that the same is substantially uniformly distributed over an area which may be measured rather in inches. Each such area approximates the walls of the 45 cross channels through the saddle F. This saddle F, in addition to its service in distributing electro-static stress, likewise distributes mechanical stress over a very considerable area so that the necessary diameter 50 for the insulating tubes 16 and 17 may be greatly reduced and still successfully resist both puncture and crushing. The metallic saddle F likewise serves as an efficient heat distributor to prevent local heating of 55 the insulation. It should likewise be noted that there is a very considerable leakage surface distance between conducting parts of the two yokes.

Each of the yokes is mechanically stayed 60 in addition to the staying effected by the saddle F in planes at right angles to each other by an imbedding body of insulating material 26, preferably electrose, which has bosses 27 imbedding the outer ends of the 65 yoke D and bosses 28 imbedding the outer

ends of the yoke C, and hips 29 enveloping the ends of the cross bar 1 and hips 30 enveloping the ends of the cross bar 2. The central portion of the contour of this imbedding insulating material is preferably 70 formed as an equatorial ring 31, the surface of which merges into the bosses and hips and the remainder of the contour of which is substantially spherical. The actual contour lines are preferably such as to conform to the electro-static flow lines of the entire structure which is symmetrical about the median plane between the cross bars 1 and 2, but the symmetry is such that the construction on one side of the plane is rotated 90° from the construction on the opposite side of said plane. 75

This imbedding body 26 of insulating material weatherproofs all the parts, and adds to the insulation between the yokes. 80

In connecting my insulator units such as A and B in a string, the eyes of the eye-bolts 13 of a yoke C are each individually directly linked by a suitable flexible connection with the eyes of the eye-bolts 13 of 90 a yoke G of the next contiguous insulator. A suitable connecting means is a C-link 31'. By this method of interlinkage a straight line pull is provided between the tension legs of each interconnected yoke so that 95 there is no tendency to bend a pair of legs such as 3 and 4 together at their outer ends.

However, the ends of a string of insulators are preferably connected with a support or the part to be supported through 100 the medium of a straddling shackle 32 having eyes 33 to be connected each with an eye of eye-bolt 13 in any suitable manner as by a C-link 31'.

Although I have described a preferred 105 embodiment of my invention in detail, it is to be understood that my invention is by no means limited to the detailed construction described, but has the full breadth and scope of the following claims, some of which 110 are not even limited to an interlinked relation of the yokes.

What I claim and desire to secure by United States Letters Patent is:—

1. A strain insulator comprising two 115 substantially U-shaped metallic tension structures each comprising a pair of tension legs and a cross-piece, said structures being located respectively in planes perpendicular to each other and with said legs symmetrically positioned about the intersection of said planes; tubular insulating means surrounding each cross-piece; a stress-distributing metallic connecting saddle for each of said cross-pieces comprising a block having 125 right angularly positioned cross-channels to fit said tubular insulating means; and a body of insulating material enveloping said tension structures and saddle.

2. An insulator comprising two relatively 130

separated crossing bars adapted to be subjected to widely different potentials; a tube of insulating material about each of said bars at the locality of crossing; and a saddle 5 of conducting material having crossing channels, one for each said tube of insulating material, for distributing the stress between said bars.

3. A strain insulator comprising a pair 10 of yokes each having a pair of separated tension legs, said pairs extending in opposite directions and a cross-bar connecting the inner ends of each pair of tension legs, each said cross-bar comprising a metal tube reinforced by an internally positioned metal pin; and insulating material interposed between said cross-bars.

4. A string of strain insulator units, each 20 said unit comprising a pair of tension yokes, each having a pair of tension legs, said pairs of legs extending in opposite directions in planes at right angles to each other; and a flexible connection directly connecting each said tension leg of each unit with the corresponding tension leg of the contiguous unit, whereby a straight line pull from tension leg to tension leg is insured.

5. A high tension strain insulator comprising a pair of interlinked yokes comprising 30 cross bars and tension legs; a tube of insulating material for each cross bar; and a metallic saddle interposing a body of metal between said tubes of insulating material and at least partially embracing the same.

6. A high tension strain insulator comprising 35 a pair of interlinked yokes comprising cross bars and tension legs; a tube of insulating material for each cross bar; a metallic saddle interposing a body of metal between said tubes of insulating material and 40 at least partially embracing the same; and a metallic electro-static stress distributor bridged between the outer ends of said tension legs.

7. A strain insulator comprising a metallic 45 bar threaded at its ends; a pair of tension legs having eyes having engagement respectively with the ends of said bar; a nipple for each tension leg having threaded engagement therewith, and an eyebolt seated 50 in each said nipple; and a body of insulating material for said structure.

8. A strain insulator for high potential duty comprising a pair of metal yokes each 55 having a pair of separated tension legs and a crosspiece connecting the inner ends of each said pair of tension legs; a metal connector located between the cross-piece of one yoke and the cross-piece of the other yoke and serving mechanically to connect said 60 cross-pieces and to distribute both electrical and mechanical strains therebetween; and a separate barrier of insulating material between each said cross-piece and said metal connector, whereby the effect of series connected insulation is effected. 65
